(57) **CLAIM**

The ornamental design for a curved toy stove, as shown and described.

DESCRIPTION

FIG. 1 is a perspective view of a curved toy stove, showing my new design;

FIG. 2 is a front elevation view thereof;

FIG. 3 is a top plan view thereof;

FIG. 4 is a left side elevation view thereof;

FIG. 5 is a right side elevation view thereof; and,

FIG. 6 is a rear view thereof.

The child and all other elements shown in phantom lines is shown for environmental purposes only, and forms no part of the claimed design.
